UNITED STATES PATENT OFFICE

117,946

DESIGN FOR A RANGE

Edward S. Criddle, Franklin, Tenn.

Application April 7, 1939, Serial No. 84,110

Term of patent 3½ years

To all whom it may concern:

Be it known that I, Edward S. Criddle, a citizen of the United States, residing at Franklin, in the county of Williamson and State of Tennessee, have invented a new, original, and ornamental Design for a Range, of which the following is a specification, reference being had to the accompanying drawing, forming part thereof.

The figure is a perspective view of a range showing my new design.

That side of the range not shown in the drawing is substantially plain.

I claim:

The ornamental design for a range, as shown and described.

EDWARD S. CRIDDLE.
